HIGH VOLTAGE ELECTRICAL CIRCUIT-BREAKERS

Marcel Charles Perolini, Neuilly-sur-Seine, France, assignor to Societe Generale de Constructions Electriques et Mecaniques (Alsthom), Paris, France, a French body corporate

Filed Sept. 14, 1960, Ser. No. 55,984

Claims priority, application France Sept. 23, 1959
3 Claims. (Cl. 200—48)

The present invention relates to high voltage electrical circuit-breakers which, to effect standardisation and for other technical reasons, comprise a plurality of series-connected units.

It is an object of the invention to enable circuit-breakers of different voltages to be made up from basic units each constructed for a given nominal voltage.

It is another object of the invention to enable very high voltage breakers, which cannot be used due to changes in conditions of utilisation of the electric supply mains, to be transformed into apparatus operable at lower voltages.

It is a further object of the invention to reduce the height of circuit-breaker installations and to simplify their construction and increase their operational safety.

These and other objects will become clear from a consideration of the specific description which is to follow.

In order that the invention may be more clearly understood, reference will now be made to the accompanying drawings which show certain embodiments thereof by way of example, compared with prior arrangements, and in which:

FIGURES 1 and 2 show schematic examples of basic pole units for circuit-breakers of known kind,

FIGURE 3 shows a known arrangement of side-by-side assembly of three units,

FIGURES 4, 5 and 6 show assemblies of three units, according to the invention, and

FIGURES 7 and 8 show further kinds of units which may be used in assemblies according to the invention.

All the units and members shown in the drawings are schematically illustrated and do not represent actual practical examples. In the drawings, like reference numerals refer to like parts.

Referring to the drawings, FIGURES 1 and 2 show examples of stacks of elementary basic circuit-breakers constituted according to known arrangements and comprising: an insulator 1 having a circuit-breaking device enclosed therewithin, release chamber 2, a supporting insulator 3 in which the control insulating tube 4 is mounted a casing 5 containing control mechanism for moving the movable contacts of the circuit-breaker or a casing 6 in which is located a hydraulic or pneumatic jack which is directly coupled to the said movable contacts. In all these modifications which are given by way of non-limiting examples, the apparatus may be either placed on a frame or suspended from a framework (not shown in FIGURES 1 and 2).

In order to make circuit-breakers operable at higher voltages, for example three times or nearly three times the elementary voltage, it is already known to assemble side-by-side, three basic units according to the arrangement shown in FIGURE 3. These units are situated in the same vertical plane or at the apices of a triangle. The circuit-breaking device 1 with the release chamber 2, of each unit are placed in series by means of the connections 7, the external electrical connections being effected at 8.

The total height of the apparatus is substantially equal to three times the height of a circuit-breaking device 1 plus three times the height of a casing 6. This arrangement is therefore very high and generally requires that

2

the elements of the circuit-breaker be reinforced in order to support the flexing efforts due to the connections and to the wind. They mostly involve the use of three supplementary cross pieces 9 having the same height as the casings 6.

FIGURE 4 shows an example of assembly according to the invention of three basic units. The three circuit-breaking devices 1 are directly placed one behind the other, the jacks in casings 6 being all placed at the same level. The number of elements making up the construction is the same as that of the basic known apparatus e.g. as shown in FIGURE 3, but the total height of the apparatus is considerably reduced, the latter being only substantially three times the height of a contact-breaking device 1 plus the height of one casing 6. No supplementary crosspieces 9 are necessary.

In FIGURE 4 the three columns constituting a stack are shown in the same vertical plane. But they need not be in the same plane and in the case of three columns for example they may be disposed at the apices of a triangle.

The three casings 6 are shown fixed to a frame 10 which serves for location of the stack assembly on insulating supports 11.

The connection by means of the frame 10 is shown by way of example but the columns could be secured together in any other manner, for example laterally by the casings 6 or by the collars of the supporting insulator 3. Similarly it is possible, in the case of suspended apparatus, to avoid all rigid connection between the three columns, it being possible to suspend each of them separately.

FIGURE 5 shows an example of circuit-breaker also with three columns, constituted according to the invention and by means of basic apparatus of the type shown in FIGURE 2. In this case the three casings 5 containing the actuating mechanisms may be aligned and assembled by lateral lugs or feet 12 and thus constitute a rigid frame enabling the apparatus to be placed on insulating supports 11. This arrangement moreover enables the three mechanisms to have their controlling members mechanically connected together, for example by connecting rods 13, which ensures that the three elements function simultaneously.

FIGURE 6 shows an arrangement which is similar to that of FIGURE 5, but in which the highest column is placed at the centre which enables the centre of gravity to be brought near to the axis of the whole circuit-breaker. This arrangement, which is also usable when jacks are utilised instead of the control mechanisms schematically illustrated, is particularly advantageous for circuit-breakers of the suspended type, it being then possible to effect the fastening by means of the centre column, approximately on the axis of the latter.

The embodiments shown by FIGURES 4, 5 and 6 relate to circuit-breakers having three columns; similar arrangements could of course be used in the case of circuit-breakers having two columns or having more than three columns.

The arrangements described above may be made also from basic apparatus such as those shown in FIGURES 7 and 8. In fact the elements constituting these apparatus are to be found in the arrangements shown in FIGURES 4, 5 and 6.

I claim:

1. A high-voltage circuit-breaker assembly comprising a plurality of columns each of which contains a circuit-breaking device mounted above a control means therefor, and wherein at least one of said columns also includes at least one supporting insulator, the several said control means all being located at the same height, and said at least one supporting insulator being located between the control means and the circuit-breaking device of

at least one of said columns, for positioning the said several circuit-breaking devices all at different heights, and means for connecting all said circuit-breaking devices electrically in series.

2. A high-voltage circuit-breaker assembly, comprising a plurality of columns each of which columns contains a circuit-breaking device mounted above a control means therefor, means interconnecting the several said control means at the same height into a rigid assembly, and wherein in at least one of said columns also includes at least one supporting insulator, said at least one supporting insulator being located between the control means and the circuit-breaking device of at least one of said columns, for positioning the said several circuit-breaking devices all at different heights, and means for connecting all said circuit-breaking devices electrically in series.

3. A high-voltage circuit-breaker assembly comprising a three columns, a first one of said columns comprising a first circuit-breaking device mounted above a control means therefor, a second one of said columns comprising 20 a second circuit-breaking device mounted above a sup-

porting insulator and said supporting insulator being mounted above a control means for said second circuit-breaking device, and a third one of said columns comprising a third circuit-breaking device mounted above two supporting insulators in vertical alignment, with said two supporting insulators mounted above a control means for said third circuit-breaking device, said three control means being mounted on a common rigid frame whereby all said control means are all located at the same height, and each of said supporting insulators being of the same height whereby said three circuit-breaking devices are all located at different heights, said third column thus being taller than said first and second columns and being mounted between them, and means for connecting all said circuit-breaking devices electrically in series.
